Patented Dec. 31, 1918.

Inventor

Gustave A. Leimecke

By *Gustave A. Leimecke*

UNITED STATES PATENT OFFICE.

GUSTAVE A. LEIMECKE, OF ST. LOUIS, MISSOURI.

BAG-HOLDER.

1,289,830.

Specification of Letters Patent. Patented Dec. 31, 1918.

Application filed February 5, 1918. Serial No. 215,460.

To all whom it may concern:

Be it known that I, GUSTAVE A. LEIMECKE, a citizen of the United States, residing at St. Louis, Missouri, have invented a certain new 5 and useful Improvement in Bag-Holders, of which the following is a full, clear, and exact description, such as will enable others skilled in the art to which it appertains to make and use the same, reference being had 10 to the accompanying drawings, forming part of this specification.

My invention relates to a bag holder of the type particularly intended for use in mail or postal cars for supporting and holding in open position, mail bags or pouches while the same are being filled, and said holder capable of being readily shifted into an out-of-the-way position while temporarily out of service.

20 The principal objects of my invention are, to provide a simple and convenient bag holder which will be effective in holding the mouth of a bag or mail pouch in full open condition while said bag is being filled; further, to provide a simple form of bracket or support for the holder which will permit the latter to be readily shifted from one position to another, and said holder and its supporting means being very compact and 30 occupying comparatively little space while not in use.

With the foregoing and other objects in view, my invention consists in certain novel features of construction and arrangement of 35 parts, hereinafter more fully described and claimed, and illustrated in the accompanying drawings, in which—

Figure 1 is a top plan view of a bag holder of my improved construction with dotted 40 lines showing a bag or mail pouch supported by the holder.

Fig. 2 is a sectional view taken approximately on the line 2—2 of Fig. 1.

Fig. 3 is an enlarged detail section taken 45 approximately on the line 3—3 of Fig. 1.

Fig. 4 is a front elevational view of a bracket which forms the fixed support for the holder.

Fig. 5 is an enlarged detail section taken 50 approximately on the line 5—5 of Fig. 2.

Referring by numerals to the accompanying drawings which illustrate a practical embodiment of my invention, 10 designates a plate which is secured in any suitable 55 manner to a support such as a wall or post, and formed integral with or fixed to said

plate is a horizontally disposed tubular housing 11. Formed in the front wall of this housing is a slot 12, one end of which terminates in a notch 13, the same occupying 60 a position approximately in horizontal alignment with the center of the housing 11 and the other end of this slot 12 extends downward as designated by 14 and said downwardly extending portion terminating at a 65 point directly below the axis or longitudinal center of the housing 11. Loosely mounted within this housing is a cylindrical member 15, preferably of metal and seated therein is one end of a short rod or pin 16, the same 70 extending outward through slot 12. This member 15 is adapted to rotate freely and slide lengthwise through housing 11, and consequently pin or rod 16 can be moved through slot 12 so as to occupy the notch 13 75 therein or the extreme lower end 14 of said slot.

Secured in any suitable manner to the top of the tubular housing 11 is a small metal plate 17, the edges of which are turned up to 80 form a holder for a cardboard strip such as 18. Secured in any suitable manner to the outer end of pin or rod 16 is the rear rail 19 of the bag holding frame, said rail being preferably in the form of a tube. Connected 85 in any suitable manner to the ends of this rear rail are tubular side rails 20, the same occupying planes parallel with each other.

The rear rail 19 and pair of side rails 20 constitute a three-sided frame to which the 90 side and rear walls of the bag or pouch is connected.

Arranged to slide freely within the tubular rails 19 and 20 are short cylindrical blocks 21 and seated in each block and projecting outwardly through a short horizontally disposed slot 22 is a hook 23. All of 95 these hooks are adapted to engage in eyelets located in the upper portions of the walls of the bag or pouch and as the blocks 21 are free to move within the rails 19 and 20, these hooks can be readily adjusted to 100 accommodate the eyelets in the bag.

When the holder is in use, the frame composed of the rails 19 and 20 is swung upward into a substantially vertical position and pin or rod 16 shifted into the notch 13 at the upper end of slot 12 with the result that the bag holding frame is supported in a firm and substantial manner and the bag 110 or pouch which is applied to said frame will be held with its mouth in full open position.

When not in use, the bag holding frame is elevated slightly to lift the pin 16 out of notch 13, and said pin is now moved downward through slot 12 until the frame 5 occupies a substantially vertical position as illustrated by dotted lines in Fig. 2.

To prevent the frame from swinging toward and away from the wall while in its out-of-the-way position, a suitable spring 10 catch *a* is secured to the wall in position to receive the lower portion of one of the rails 20 when said frame is swung downward. (See Figs. 1 and 2.) Practically all mail sacks or pouches are provided around the 15 upper edge with a draw-string *b*, the same sliding freely through a combined latch and tag holder *c*. When the bag is applied to the frame it is arranged so that the ends of this draw-string and the tag holder are 20 positioned at the front or between the forward ends of rails 20. When the mail matter has been distributed and the clerk desires to remove the bag or pouch from the rack, the latch and tag holder *c* is grasped in one 25 hand and with the other hand, the ends of the draw-string are drawn through said latch and tag holder. At the same time, the parts are given a slight upward movement, and as a result of such movement and 30 the pull upon the draw-string, the upper edge of the bag or pouch will be readily detached from the hooks 23, thus materially decreasing the time and labor involved in removing the sack or pouch from the frame. 35 It will be understood that where my improved bag holder is used in the mail service, a card upon which is printed or written

the name of a city or State can be readily inserted in the holder 17, thereby forming a guide for the proper distribution of mail 40 matter.

Bag holders of my improved construction are comparatively simple, can be easily and cheaply manufactured, and provide simple and efficient means for supporting mail bags 45 and pouches while mail matter is being distributed.

It will be readily understood that minor changes in the size, form and construction 50 of the various parts of my improved bag holder may be made and substituted for those herein shown and described, without departing from the spirit of my invention, the scope of which is set forth in the appended claims.

I claim:

1. A bag holder comprising a plate with an attached housing having a bayonet slot 60 in its side, a movable member in said housing, bag supporting arms, and a pin rigidly connecting said movable member to said arms and movable in said slot.

2. In a device of the class described, a rigidly fixed housing provided in its side 65 with a bayonet slot, a member loosely mounted in said housing, a pin seated in said loosely mounted member and movable through the bayonet slot in the housing, a frame secured to said pin, and bag engaging hooks on said frame.

In testimony whereof I hereunto affix my signature this 2nd day of February, 1918.

GUSTAVE A. LEIMECKE.
